UNITED STATES PATENT OFFICE.

JOHN S. WATTERS, OF VINCENNES, INDIANA.

DESIGN FOR A COMBINED RADIOCABINET AND LOUD SPEAKER.

Application filed March 7, 1925. Serial No. 12,640. Term of patent 7 years.

To all whom it may concern:

Be it known that I, JOHN S. WATTERS, a citizen of the United States, residing at Vincennes, in the county of Knox, State of Indiana, have invented a new, original, and ornamental Design for Combined Radiocabinets and Loud Speakers, of which the following is a specification, reference being had to the accompanying drawing, forming part thereof.

The figure is a perspective view of a combined radio cabinet and loud speaker embodying my invention.

I claim:

The ornamental design for a combined radiocabinet and loud speaker, as shown.

JOHN S. WATTERS.

Witness:

E. HAYWARD FAIRBANKS.
